UNITED STATES PATENT OFFICE

FREDERICK WILLIAM EAST, OF PETERSFIELD, ENGLAND, ASSIGNOR TO I. T. S. RUBBER COMPANY LIMITED, OF PETERSFIELD, ENGLAND

BOOT AND SHOE

Application filed November 23, 1929, Serial No. 409,357, and in Great Britain May 27, 1929.

This invention refers to improvements in or relating to boots and shoes, and it has more particular reference to studs for the soles and heels of football boots and the like.

5 Heretofore it has been the common practice in connection with football boots and the like, to provide the soles and heels thereof with nailed-in leather studs, the nails passing through the several lifts of which the 10 studs are usually formed and entering the leather sole. Some considerable difficulty, however, is experienced in obtaining a proper fixing when the soles of such boots are formed of rubber or the like, and it is with the object of avoiding this disadvantage and of 15 enabling the studs to be firmly secured thereto, that the present invention has been devised.

Now according to the present invention 20 I provide a boot or shoe for football or other sports wear or the like in which the sole or tread portion thereof is formed of vulcanized rubber or the like having a plurality of metal "inserts" or ferrules provided in connection therewith and which are screw-threaded for engagement with the screwed shanks provided on the studs.

In order that the present invention may be clearly understood and more readily carried into effect, it is hereinafter described with reference to the accompanying drawings, in which:—

Figure 1 is a plan view of a football boot showing one of the studs removed;

35 Figure 2 is a side elevation thereof;

Figure 3 is a detail sectional side elevation of a portion of the tread showing the ferrule embedded therein;

Figure 4 is a corresponding plan view 40 thereof;

Figure 5 is a sectional perspective view of one of the studs;

Figure 6 is a plan view thereof; and

45 Figures 7, 8 and 9 are side elevations of different sizes of studs suitable for different conditions.

As shown, I provide the studs 10 with a projecting portion or shank 11 which is adapted to pass through and to co-operate 50 with a metal ferrule or plate 13 which may

be embedded, during the process of manufacture, in the sole and/or heel portion of the boot. The studs 10 may conveniently be formed of vulcanized rubber or the like and they may be provided with a projecting screw 55 stem 11 the inner portion of which is suitably shaped, as at 12, and embedded in the material thereof so as to provide a firm fixing and prevent rotation. The projecting stem 11 is screw-threaded and is adapted to co-operate with an embedded ferrule 13 provided in the sole or heel portion 14 of the boot, the ferrule 13 also being suitably shaped or headed, as at 15, or perforated, so as to give it a firm fixing in the material 14 of the sole 60 or heel. If desired, the plates may be made square, or of hexagonal or other shape, and they may be punched out with projections to prevent turning and to secure a good anchorage. The ferrule 13 is preferably moulded flush with or just below the outer surface of the sole 14 and is perforated, as at 17, and internally screw-threaded so as to provide a screwed socket 18 with which the projecting 65 screwed stem or shank 11 on the stud 12 is adapted to co-operate. The screwed plate and ferrule 13 is preferably of slightly less thickness than the sole or heel plate 14 in which it is embedded, so as to leave a portion of the rubber or fabric 22 thereof unperforated on the inner side, thus preventing the ingress of water to the boot. The flush surface of the embedded plate or ferrule and/or the surrounding surface of the sole 14 and/or the co-operating surface 19 on the base or 70 underside of the stud are formed so as to provide an interlocking engagement. To this end radial serrations or ribs 20, 21 may be formed or moulded on the said co-operating surfaces. In the case of a football boot, a plurality of such screwed-in studs 10 would be provided, two conveniently being arranged, as shown, one on each side of the heel, and four at suitable distances apart on the sole. 75

The studs themselves 10 may be conic frustums or of cylindrical formation having plain outer surfaces, or they may be otherwise suitably shaped or roughened or provided with projections to increase the grip. In 80

the case of Alpine or other sports boots or shoes, the studs may be provided with projecting pins of metal or the like, or, alternatively, the whole of the stud may be formed of metal.

5 The sole 14 may, as shown be backed by canvas 22 which may be proofed with rubber, or otherwise treated to secure adhesion to give rigidity to the sole and may be used in either single or multiple plies. If desired, the screwed "inserts" 13 may be placed between such ply to obtain better anchorage.

10 In a slightly modified construction it may be found desirable to make the ferrules in the form of eyelets which are adapted to be inserted and fixed in place in the soles after they are vulcanized, the eyelets being screw-threaded as before, to engage the screwed shanks of the removable studs and also having radial or serrations on their outside surface adapted to co-operate with the corresponding ribs or serrations formed on the bases of the studs.

15 By this invention it will be found to be possible to provide a fixing arrangement whereby studs can be securely attached to the soles and heels of football and like boots. A further advantage accompanying the use of the improved studs is that they can be removed when worn and replaced by new ones, without in any way damaging or impairing the strength and durability of the sole. Further, in the case of football boots the studs could be made of different sizes, as indicated in Figures 7, 8 and 9, those shown in Figure 7 being suitable for Association football in dry weather; those in Figure 8 for Association football in wet weather; and those shown in Figure 9 being best suited for Rugby football. In some cases sets of studs of different sizes may be provided for use in connection with a single pair of boots, the sets being exchanged to suit the play or weather or the purpose for which the boots are to be used. 20 Where more permanent fixing of the studs is desired, cement or rubber solution may be used when securing these in place. The interengaging metal portions may be made of rustless or other steel or metal, as may be found to be most suitable in practice or desirable from a commercial or economical point of view.

25 In some cases, in order to afford further support to the studs and in order to prevent their being kicked or broken off, a buttressed ridge may be provided on the surface of the sole in order to provide a depression into which the base of the stud is adapted to nest. Alternatively, the depression or circular cavity may, if desired, be formed in the thickness of the sole itself. Both these arrangements also serve to provide a more watertight junction between the stud and the sole.

30 What I claim is:—

65 In sport footwear, a ferrule embedded in

the sole and having an upper flange to be embedded in and interlocked with the material of the sole coincident with the upper surface thereof, said ferrule including a hollow threaded section extending toward and terminating short of the outer surface of the sole, the opening in the sole beyond the threaded portion being substantially coincident with the opening in the threaded portion to thereby provide a portion of the sole underlying the free edge of the threaded portion, the outer surface of the sole surrounding the opening being integrally formed with locking projections, and a stud having an upper surface substantially coincident in area with that portion of the sole formed with the locking projections, said upper surface of the stud being formed with projections adapted to interlock with the projections of the sole, and a shank embedded in the stud and extended above the upper surface thereof as a threaded projection to cooperate with the threaded portion of the ferrule, the projecting length of the shank beyond the stud being less than the threaded portion of the ferrule whereby the shank may be united to the ferrule to compel a pressure interfit of the locking projections on the sole and on the stud.

70 In witness whereof I have hereunto signed my name.

75 FREDERICK WILLIAM EAST.
